UNITED STATES PATENT OFFICE.

HENRY B. FORD, OF NEW YORK, N. Y., ASSIGNOR TO PERKINS & WELSH, OF SAME PLACE.

STUFFING-BOX FOR AIR OR GAS PUMPS.

SPECIFICATION forming part of Letters Patent No. 363,456, dated May 24, 1887

Application filed October 13, 1886. Serial No. 216,109. (No model.)

To all whom it may concern:

Be it known that I, HENRY B. FORD, of the city, county, and State of New York, have invented a new and useful Improvement in 5 Stuffing-Boxes for Air or Gas Pumps, of which the following is a specification.

My invention relates to a new form of stuffing-box, especially designed for air or gas pumps.

10 My invention consists in the construction and arrangement of the box, hereinafter set forth, whereby any escape of gas from or entrance of air into the pump-cylinder is effectively prevented.

15 In the accompanying drawings, Figure 1 is a vertical transverse section of my improved stuffing-box. Fig. 2 is a horizontal transverse section on the line *xx* of Fig. 1.

20 Similar letters of reference indicate like parts.

A is the pump-piston. B is the cylinder-head, the remainder of the cylinder not being shown. C is the pump piston-rod.

25 In the cylinder-head B is formed a cavity or recess, D. On the piston is a projection, E, adapted to enter said cavity. The pump-cylinder is intended to stand vertically, as indicated in the drawings, the stuffing-box, hereinafter described, being located upon the lower 30 cylinder-head. Projecting from said cylinder-head is an annular casing, F, which is open below, and which encircles the piston-rod. The space adjacent to the cylinder-head and surrounding the piston-rod is packed, as indicated at G, with any suitable packing material. Surrounding the casing F is the body H of the box, which may tightly fit upon said casing, or be formed or otherwise secured thereon in any suitable way. The upper portion, I, of said box is enlarged, and is of greater 35 diameter than the lower portion, J.

40 Entering the casing F is a packing-ring, K, which bears upon the packing G. Entering the smaller portion, J, of the box H is a similar packing-ring, L. The rings K and L are connected by rods M, which enter the annular space between the casing F and rod C. Below ring L, and contained in the part J of the box H, is the cover O. Said cover may be driven 45 in to make a tight fit, or be provided with a screw-thread to enter a corresponding thread

in the part J, or be connected to said part in any other well-known way.

Passing through the part I of box H and into the annular space inside the casing F are 55 two tubes, P and Q. Said tubes are provided exteriorly with suitable covers. In the upper part, I, of box H is also arranged a valve, R, of any ordinary construction, and adapted to open inward when the exterior air-pressure is 60 greater than that existing within the box. The parts, as above described, are assembled in the following manner: The casing F and box H may, as already stated, be made in one piece or be secured together. The packing G 65 is placed within the casing F, and the packing-rings K and L are put in place upon the piston-rod. The packing N is then put in the box H, and finally the cover O is tightly driven or screwed in, so as firmly to compress the 70 packings around the rod. The tubes P and Q then being opened, the whole interior space of the box is filled with (preferably) oil, and the tube-covers are replaced.

75 This stuffing-box operates to keep air out of the pump in the following manner. It is of course manifest that air can enter only when there is a partial vacuum between cylinder-head B and piston A. In such case, if an ordinary stuffing-box were used, the outside atmosphere would force itself between pump-rod and packing, and so enter the cylinder; but in the present case this is impossible. Any air which might tend to enter around the rod through the cover C and packing N is met by 80 the column of oil. Furthermore, the air will not come in from below, because when the oil-pressure is diminished the valve R opens inward. Hence the worst result of the vacuum in the pump-cylinder is to cause a little oil to 85 be drawn into the pump-cylinder; but this is scarcely possible, because the same pressure which tends to force the oil into the cylinder causes it to act upon the ring K, to cause the latter to press the harder upon the packing G. 95 If, however, any oil should enter the cylinder, it will accumulate in the recess D, and out of this recess it will be squeezed and forced back into the box by the entry into said recess of the projection E.

100 When there is a high pressure of gas between piston and cylinder, the stuffing-box operates

to prevent escape of gas as follows: Any gas which might get out of the cylinder would first have to pass between the rod C and packing G. It could get no farther, because it would 5 meet the oil. Pressure upon the oil would simply force the valve R the more tightly, and shut and crowd the ring L down upon the packing N, so that the oil would bar the further escape of gas, and be itself prevented from 10 being forced out by the tight packing N and the closed valve R.

I claim—

1. In a stuffing-box for air or gas pumps, the box H, containing a liquid such as oil, 15 inner casing, F, packing-rings K and L, pack-

ing G N, cover O, and a means—such as pipes P Q—for introducing the oil into said box H, substantially as described.

2. In a stuffing-box for air or gas pumps, the box H, containing a liquid such as oil, 20 inner casing, F, connected packing-rings K and L, packing G N, cover O, valve R, and a means—such as pipes P Q—for introducing the oil into said box H, substantially as described.

HENRY B. FORD.
